UNITED STATES PATENT OFFICE.

WILLIAM A. BESSERDICH, OF CLINTONVILLE, WISCONSIN.

INTERNAL-COMBUSTION ENGINE.

1,113,743.

Specification of Letters Patent. Patented Oct. 13, 1914.

Application filed June 10, 1912. Serial No. 702,864.

To all whom it may concern:

Be it known that I, WILLIAM A. BESSERDICH, a citizen of the United States, residing at Clintonville, in the county of Waupaca and State of Wisconsin, have invented 5 certain new and useful Improvements in Internal-Combustion Engines; and I do hereby declare the following to be a full, clear, and exact description of the invention, such as will enable others skilled in 10 the art to which it appertains to make and use the same.

This invention relates to internal combustion engines, and it more particularly 15 relates to an improved valve mechanism for fluid pressure engines.

An object of the invention is to provide 20 an engine of this character having two counterpart valve mechanisms, oppositely disposed, and having oppositely disposed fluid passages or ports communicating with a main cylinder and adapted to be used alternately for the in-take and exhaust or outlet of the actuating fluid.

A still further object of the invention is 25 to provide an engine of this character, the main cylinder and oppositely disposed valve chambers of which, together with the guides for the valve-actuating piston rod, are all formed integrally, or constitute a unitary 30 casting, and thereby combine simplicity, compactness, rigidity and economy of manufacture, with thorough efficiency.

Another object is to generally improve 35 fluid pressure engines of this character.

With these objects in view the invention consists in the improved construction, arrangement and combination of parts of a device of the character described which will 40 be hereinafter fully described and afterward specifically claimed.

In the accompanying drawings which 45 form a part of this application, Figure 1 is a vertical sectional view through the main casting or body of the engine and through the main piston and slide valves, the movements of the engine being illustrated diagrammatically. Fig. 2 is a horizontal sectional view taken on the line 2—2 of Fig. 1, and, Fig. 3 is a horizontal sectional view taken on the line 3—3 of Fig. 1.

Referring to these drawings, in which 50 similar reference characters correspond with similar parts throughout the several 55 views, the main cylinder 5 merges with the combustion chamber 6 and carries the main

piston 7; the latter being pivoted at 8 to a connecting rod 9 which is pivoted at 10 to a crank 11 on the crank shaft 12. A gear wheel 13 is also secured on the crank shaft 60 12 and is in mesh with gear wheels 14 and 15, the latter being seated on shafts 17 and 18, the latter carrying cranks 17' and 18', respectively, which are pivoted at 19 and 20 to connecting rods 21 and 22 respectively. 65 These connecting rods are pivoted at 23 and 24 to rods 25 and 26, respectively, which are secured to cylindrical slide valves 27 and 28 respectively. These slide valves may be of any proper and desired construction, although I have shown the same constructed 70 in two sections. The main section 29 of each slide valve is screw threaded at 30 to a spider 31, said spider being centrally apertured at 32 and in screw threaded engagement with the respective valve rods 25 and 26.

Each valve piston rod is formed in two sections, the adjacent ends of which are provided with a turn-buckle 33, whereby the 80 position of each slide valve may be adjusted within the valve chambers 34 and 35. The valve chambers 34 and 35 are provided with fluid passages 36 and 37, either of which is adapted to be connected with any 85 proper source or supply of actuating fluid. In practice, however, only one of these passages is connected with a fluid supply, while the other may be connected to a muffler, or allowed to communicate directly with the 90 open air, so as to lead off the exhaust gases or products of combustion. In the present instance, I have chosen to assume that the passage 36 is the primary inlet passage, while the passage 37 is the final exhaust 95 passage, so that while, in the position shown, no gas is entering or being exhausted, the directions in which the gas is assumed to enter and in which the exhaust is 100 assumed to escape are indicated by the broken arrows.

The spiders 32 are provided with apertures or passages 38, which establish communication between the lower portions of the valve cylinders or chambers and the interior portions of the hollow cylindrical valves 27 and 28, the upper portions of said valves being in communication with the upper portions of the respective valve cylinders.

A series of parallel and horizontally disposed ports 39 establish communication be-

tween the main cylinder 5 and the valve chamber 34, while a similar and oppositely disposed series of ports or passages 40 establish communication between the main cylinder and the valve chamber 35. As more clearly shown in Fig. 2, the passage 39 is divided by a series of bridges 41, a similar series of bridges 42 being provided between ports or passages 40; these bridges being for the purpose of supporting the packing rings 41', located in grooves in the peripheries of valves 27 and 28 as they are carried past said ports. By this arrangement of the inlet and exhaust ports 39 and 40, respectively, provision is made for a large and quick supply or in-take of gas and for a quick exhaust of the products of combustion, so as to reduce the power required for the suction and exhaust strokes, to a minimum; since it will be seen that the horizontal distance through these ports is very much greater than the vertical distance therethrough, and so, these ports are opened and closed by a very slight movement of the valve, and so that the ports are opened during a relatively small portion of each cycle of the engine.

In operation, assuming that the cranks 11, 17' and 18' are moving in the direction of the several arrows, and that combustion has just taken place in the chamber 6, it will be seen that the ports 39 and 40 are closed by the piston 7, so that the valves are entirely relieved of or guarded from the force of the explosion, while the piston 7 receives the full force thereof. The relative proportions of the gear wheels 14 and 15 to the gear wheel 13 is such that the latter makes two revolutions while the former are making one, so that when the piston 7 has forced the crank 11 from the position *e* to the position *f*, the crank 17' will have moved from the position *a* to the position *b*, and in doing so, passes through position *g* and thereby moves the valve 27 to position *i* and returns it to the position shown in Fig. 1; and while the crank 18' is moving from the position *a'* to the position *b'*. The piston 7 having completed its working stroke, starts back on its exhaust stroke, and while the crank 11 moves from position *f* to position *e*, the crank 17' moves to position *c*, bringing the valve 27 to position *j*; and at the same time, the crank 18' moves to position *c'*, passing through position *h'*, and in doing so, brings the valve 28 to position *k'* and returns it to position *j'*, thereby opening and closing the exhaust port 40 while the piston 7 is making its exhaust stroke. The piston 7 now starts down on its suction stroke, the crank 11 moving again from position *e* to position *f*, and when said crank has reached the position *m*, the crank 17', has reached the position *h*, in which position the port 39 is wide open, the top of the piston 27 being in position *k*, and when crank 11 has reached position *f*,

the crank 17' has reached position *d* and, the valve 27 has been returned to position *j*, closing the port 39; and at the same time, the crank 18' has moved to position *d'*, thereby returning the valve 28' to the full line position as shown. The piston 7 now starts upward on its compression stroke, and when it has reached the full line position shown, the crank 17' will have reached the position *a*, thereby carrying the valve 27 to its full line position, as shown, and the crank 18' will have passed through position *g'*, to position *a'*, thereby raising the valve 28 to position *i'* and lowering it again to its full line position. The engine has now completed a cycle, and is ready for the next explosion, after which the foregoing operation will be repeated with each succeeding cycle.

It will be seen that the valve which opens and closes the exhaust port, moves one quarter of a revolution in advance of the valve which opens and closes the inlet port.

Any proper means may be employed for supplying lubricating material to the main piston, and oil ducts 43 are provided through the walls of the casting which separate the main cylinder from the valve cylinders, said oil ducts communicating with said cylinders and being downwardly inclined in the direction of the valves; the valve cylinders being provided with annular grooves or oil passages 44 which are adapted to register alternately with the ducts 43, and through the medium of these ducts, oil from the main cylinder may be transmitted to the valve cylinders, for lubricating the latter.

In order that the valve cylinders may be easily cleaned, when necessary, I provide each of said cylinders with a cylinder cap or head 45 which is screw threaded into the cylinder, and is provided with prismatic lug 46, for engagement with any proper tool, for removing the cylinder heads.

Any proper form of spark plug, as indicated at 47, may be employed, and adapted to coact with any proper means (not shown), for igniting the combustible fluid.

The main cylinder and the valve cylinders are surrounded by a water-jacket chamber 48 and the ports 39 and 40 are also surrounded by said chamber, so that heating of the entire casting is reduced to a minimum.

It is obvious, from the preceding paragraphs and from the drawings, that each of the ports 39 and 40 respectively, are closed through more than three quarters of each cycle and open through less than one quarter of each cycle; and it will also be obvious that the in-take port is wide open during the time that the speed of the piston 7, in the suction stroke, is the greatest, and as the in-take valve becomes more nearly closed, the speed of the piston diminishes, as it nears the completion of the suction stroke; and therefore, the opening between the valve 27 and the

port 39 is always in proportion to the suction imparted by the main piston. The foregoing relation of the piston and the intake port is applicable to the relation of said piston with the exhaust port, as is obvious. It is also quite obvious that, the undesirable passage of gas and of products of combustion through the ports, when the same are uncovered by the main piston, is avoided, 10 since the slide valves are provided with expansion rings or packing rings 41' both above and below the intake and exhaust ports.

On account of the unusually capacious intake port, and on account of the manner in which said port is closed and opened, it will be seen that after each compression stroke, the main piston confines a considerable quantity of gas within said port. When the primary explosion takes place, the port 39 is closed, so that the gas within the port is not immediately exploded; but, immediately after the primary explosion, and while the heat thereof is intense, the main piston 25 moves downward and uncovers the port, releasing a secondary charge of gas therefrom, so that said secondary charge is immediately ignited and produces a secondary explosion, thereby imparting additional impetus to the main piston, during each working stroke thereof.

I do not limit my invention to the exact details of construction, combination and arrangement of parts as illustrated and specified, but my invention may only be limited by a reasonable interpretation of the claims.

I claim:—

1. In an internal combustion engine, a main cylinder, a main piston in the main cylinder, a valve cylinder, a valve in the valve cylinder, and a partition between the main cylinder and the valve cylinder, said partition having a port in communication between said main cylinder and said valve cylinder,

inder, said partition having an inclined oil duct communicating with the main cylinder and with the valve cylinder, said valve having oil passages adapted to communicate alternately with the oil duct.

2. In an internal combustion engine, a main cylinder, a pair of valve cylinders on opposite sides of the main cylinder, a main piston in the main cylinder, a slide valve in each valve cylinder, a gas intake port communicating between the main cylinder and one valve cylinder and an exhaust port communicating between the main cylinder and the other valve cylinder, said main cylinder having a chamber for the explosion of gas and said main piston having an annular flange for covering both of said ports at the moment of explosion.

3. In an internal combustion engine, a main cylinder, a piston operable therein, auxiliary cylinders carried by said main cylinder and in communication with the top thereof, said auxiliary cylinders having inlet and exhaust ports, sleeves slidably mounted in said auxiliary cylinders, spiders carried by said sleeves, piston rods connected to said spiders, ported webs connecting said main cylinder and said auxiliary cylinders whereby lubricant can pass from said main cylinder to said auxiliary cylinders, and means actuated by a movement of said piston for reciprocating said sleeves in said auxiliary cylinders, said means being timed whereby said sleeves will have a single reciprocatory movement relatively to a double reciprocatory movement of said piston.

In testimony whereof I have signed my name to this specification in the presence of two subscribing witnesses.
